UNITED STATES PATENT OFFICE

102,977

DESIGN FOR A HOISTING APPARATUS CAB

Earle F. Rueter, Milwaukee, Wis., assignor to
Koehring Company, Milwaukee, Wis., a corporation

Application October 5, 1936, Serial No. 65,174

Term of patent 14 years

To all whom it may concern:

Be it known that I, Earle F. Rueter, a citizen of the United States, residing at Milwaukee, in the county of Milwaukee and State of Wisconsin, have invented a new, original, and ornamental Design for a Hoisting Apparatus Cab, of which the following is a specification, reference being had to the accompanying drawing, forming a part thereof, in which:—

Figure 1 is a perspective view of the hoisting apparatus cab design, illustrating the front and one side portion thereof.

Figure 2 is a perspective view to a reduced scale

of the hoisting apparatus cab looking in a direction opposite from that in which Figure 1 is taken, and illustrating the rear and other side of the cab.

Figure 3 is a plan view to a reduced scale of the cab.

Figure 4 is a side elevation to a reduced scale of the cab.

I claim:

The ornamental design for a hoisting apparatus cab as shown.

EARLE F. RUETER.
